UNITED STATES PATENT OFFICE.

JOSEPH S. McMILLAN, OF REPUBLIC, MISSOURI.

CEMENT BLOCK FOR SILOS.

1,194,305.

Specification of Letters Patent.

Patented Aug. 8, 1916.

Application filed July 13, 1914. Serial No. 850,767.

To all whom it may concern:

Be it known that I, JOSEPH S. McMILLAN, citizen of the United States, residing at Republic, in the county of Greene and State of Missouri, have invented certain new and useful Improvements in Cement Blocks for Silos, of which the following is a specification.

My invention relates to new and useful improvements in silo constructions, and as its principal object aims to provide a novel form of building block which is especially adapted for the construction of silos.

A further and more specific object of my invention is to provide a building block which is formed preferably of concrete and is longitudinally curved, being equipped with longitudinally extending reinforcing rods, the terminals of which carry integral eyelets adapted to project beyond the terminals of the block and to mate with the eyelets of the reinforcing rods of the next adjacent block so that a bolt or similar fastening device may be employed in securely connecting adjacent blocks.

Another object of the invention is to so form the blocks that they may be applied in the nature of circular or ring-like sections when the silo is being constructed.

A still further object is to form, in the terminal of each block, a substantially V-shaped groove or trough so that, when the blocks of each section are assembled, there will be formed between the abutting terminals of the adjacent blocks a square passage in which mortar or some other binding material is tamped for the obvious purpose of supplementing the action of the connecting bolts in securely fastening the terminals of the various blocks to each other.

The above recited and other incidental objects of a similar nature are accomplished by such means as are illustrated in the accompanying drawings, described in the following specification and then more particularly pointed out in the claims, which are appended hereto and form a part of this application.

With reference to the drawings, wherein there has been illustrated the preferred embodiment of this invention as it is reduced to practice, and throughout the several views of which similar reference numerals design-

ate corresponding parts. Figure 1 is a side elevation of a partially constructed silo, illustrating particularly the manner in which the block is designed to be arranged in ring-like sections; Fig. 2 is a detail perspective view of a single silo section constructed of a number of my building blocks. In this figure, the abutting terminals of two adjacent blocks are broken away to more clearly disclose the manner in which the terminal eyelets of the truss rods are connected; Fig. 3 is a detail perspective view of the preferred form of block.

In the embodiment of my invention shown in the accompanying drawings, the silo, designated as an entirety by the numeral 10, is constructed from a number of ring-like sections 11. Each section is, as best illustrated in Fig. 2, constructed from a plurality of building blocks, one of which is illustrated in detail in Fig. 3. Upon reference to these last-mentioned figures, it will be seen that the blocks, which are preferably constructed of concrete, are longitudinally curved so that they may constitute a portion of a circular section, as shown in Fig. 2. At each terminal of the block, there is formed a vertically extending channel or groove 12. These grooves 12 are substantially V-shaped or trough-like in formation, so that the two grooves or channels, at the abutting terminals of the various blocks, will mate to form a square passage, as in Fig. 2. The purpose for which this square passage is provided will be hereinafter more fully explained in that portion of the specification devoted to a description of the assembling of the blocks during the construction of the silo.

In each block member there is embedded a pair of truss rods 13 and 14. These truss rods are preferably formed from wrought iron or steel, although, if desired, they may be made from strap iron, steel or any other suitable metal. The truss rods are longitudinally curved to correspond to the curvature of the blocks and are terminally provided with integrally formed eyelets 15. The rods are of such length that the eyelets will project slightly beyond the channels 12. In the approximate center of the upper face of each block there is formed, as indicated at *a*, an opening or bore, the pur-

pose of which will be hereinafter more fully explained.

From the foregoing description, taken in connection with the accompanying drawings, the construction of the building blocks will be readily appreciated. It, therefore, remains to explain the manner in which the blocks are laid when the silo is being constructed.

- 10 Upon a suitable foundation, the first section is mounted. This first section consists, as does each succeeding section, in such number of blocks as will complete a circle. The eyelets of the abutting terminals of the blocks are brought into vertical alinement with each other, so that a locking bolt or rod, indicated at 16, may be passed through them for the obvious purpose of firmly connecting the blocks. A layer of wet mortar 15 or other binding element is, of course, applied to the foundation prior to the laying of the blocks. After the first ring section has been laid, mortar is tamped into each of the squared channels defined by the troughs 20 12 so that the rods or bolts 16 will be held against shifting and the terminals of the blocks will be more firmly united. In this connection, it is also to be observed that the tamping of mortar into the squared openings between the block terminals provides, 25 in effect, a seal which will prevent the entrance of water into the silo and will also guard against escape of ensilage between the blocks. After the first section has been laid 30 on the foundation, the next section is laid in the same manner, a layer of mortar being first applied to the upper surface of the first section. The blocks of each succeeding section are arranged so that the joint between them will be staggered with respect to the 35 joints of the blocks of the adjacent sections, as is clearly shown in Fig. 1. The purpose in thus staggering the blocks of each succeeding section with respect to the blocks 40 immediately below will now be apparent, particularly upon reference to Fig. 1, in which it will be seen that each rod or bolt member 16 is of such length that its lower terminal extends down into the opening or 45 bore *a*. Obviously the lower terminals of the rods 16 being engaged in the bores *a* serve to prevent the shifting of the blocks upon each other.

In molding the blocks, the pallet is preferably so formed that the upper and lower faces of the blocks will be relatively rough so that the mortar or other binding agent will firmly grip the surface.

It will now be seen that I have provided 50 an extremely simple form of building block which is adapted especially for use in constructing silos or similar cylindrical containers. It will also be seen that I have provided a relatively simple and nevertheless 55 efficient form of fastening device for

connecting the abutting terminals of the individual blocks. It will also be noted that the truss rods constitute not only the fasteners but also serve as reinforcing elements for the block, for the truss rods being terminally connected to each other by the members 16 form in effect circumferential bands which will add materially to the ability of the silo to withstand internal and external strains.

It is to be observed that my invention contemplates the employment of longitudinally twisted rods in lieu of the rods shown in the drawings. Under some circumstances it may be desirable to provide the rods with lateral projections or protuberances at various points throughout their length as a means for holding the rods against shifting longitudinally of the block.

In conclusion, I desire to emphasize the fact that while I have designed my building blocks particularly for use in constructing silos, they are equally efficient in constructing tanks for the reception of oil, grain, ice or water.

Having thus described the invention, what is claimed as new is:

1. A silo including a plurality of arcuate blocks laid in superposed courses and arranged to break joint, the blocks of each course having flat top and bottom faces and vertical substantially V-shaped recesses formed in the opposite ends thereof and extending the entire height of the blocks, each block being provided intermediate its ends with a vertically disposed recess opening through the flat top face of the block and spaced from the bottom flat face thereof, horizontal truss members arranged within the blocks and provided with terminal eyes projecting within the V-shaped recesses, and a plurality of relatively short vertical locking rods connecting the eyes of the truss members of the blocks of each course and arranged in staggered relation with the lower extremities of the rods of each course above the bottom course extending within and housed by the recesses of the blocks of an adjacent course.

2. A silo including superposed courses, each formed of a plurality of arcuate blocks having flat top and bottom faces and vertical substantially V-shaped recesses formed in the opposite ends thereof and extending the entire height of the blocks, the blocks of each course being each provided intermediate its ends and near its outer convex side face with a vertically disposed recess opening through the flat top face of the blocks and spaced from the bottom flat face thereof, spaced horizontal truss members arranged within each block on one side of the longitudinal center thereof and provided with terminal eyes projecting within and housed by the V-shaped recesses, and a plurality of rela-

tively short vertical locking rods connecting the eyes of the truss members of the blocks of each course and arranged in staggered relation with the lower extremities of the rods of each course above the bottom course extending within and housed by the recesses of the blocks of an adjacent course.

In testimony whereof I affix my signature in presence of two witnesses.

JOSEPH S. McMILLAN. [L.S.]
